CLAIM

The ornamental design for a compact vacuum material handler as shown and described.

DESCRIPTION

FIG. 1 is a front elevation view of a compact vacuum material handler.

FIG. 2 is a right side elevation view.

FIG. 3 is a rear elevation view.

FIG. 4 is a left side elevation view.

FIG. 5 is a top plan view; and,

FIG. 6 is a bottom plan view.

The broken lines in the drawings shown portions of the compact vacuum material handler which form no part of the claimed design.

1 Claim, 3 Drawing Sheets
